US0D1063408S

(12) United States Design Patent (10) Patent No.: US D1,063,408 S
 Giorgi (45) Date of Patent:  Feb. 25, 2025

(54) FABRIC WITH PATTERN

(71) Applicant: J. Choo Limited, London (GB)
 (72) Inventor: Eliana Giorgi, London (GB)
 (73) Assignee: J. Choo Limited, London (GB)
 () Term: 15 Years
 (21) Appl. No.: 29/858,656
 (22) Filed: Nov. 2, 2022

(30) Foreign Application Priority Data

(57)

CLAIM

The ornamental design for a fabric with pattern as shown and described.

DESCRIPTION

The sole FIGURE is a front view of a fabric with pattern showing my new design.

The broken lines surrounding the FIGURE depict the boundaries of the claim and form no part thereof.

1 Claim, 1 Drawing Sheet
